2 Claims

ABSTRACT OF THE DISCLOSURE

Undesirable odors in quaternary ammonium compounds are prevented by admixing up to 2% by weight of SO₂ and then drying said compounds of solvent.

This invention broadly relates to quaternary ammonium compounds and more particularly to a method for preventing the development of undesirable odor in quaternaries, and to the composition produced therefrom.

Quaternaries, when prepared as a dry product, free of solvent, develop strong off-odors. The exact cause of this is not known but the problem is so bad that batches of quaternaries, such as di(hydrogenated tallow) quaternary ammonium chloride, must be completely discarded or reprocessed at considerable expense to remove offensive odors that have developed in the product since its manufacture. Obviously an offensive odorous product is not normally saleable especially for such use as household detergent, germicide and the like.

An object of this invention is to provide a novel process for quaternary ammonium compounds.

Another object is to provide an improved purification process for quaternaries which is economical.

Still another object is to provide a process for preventing the development of undesirable odor in quaternaries which is relatively easy to perform, even by unskilled technicians.

A further object is to provide a process which imparts 40 odor stability to quaternary amines.

A still further object is to provide a purification process which leaves no undesirable residue in the finished quaternary so that it may be further processed without subsequent deleterious effect.

Other objects of the invention will in part be obvious and will in part appear hereinafter.

The invention accordingly comprises the several steps and the relation of one or more of such steps with respect to each of the others, and the composition possessing the features, properties, and the relation of constituents, which are exemplified in the following detailed disclosure, and the scope of the invention will be indicated in the claims.

It has now been found that quaternary ammonium compounds, during manufacture or subsequently may be stabilized against odor development thereafter by the mere addition of proper quantities of sulfur dioxide (SO₂) thereto. The addition is preferably performed just prior to stripping of the reaction solvent. The quaternary may then be cooled and flaked or pulverized; or even spray dried. Thereafter the quaternary will be stable to odor, and as such is ready for use as a component in compositions where odor may be crucial or as a reactant in further synthesis. The SO₂ has no deleterious effect upon such further use, and in fact, imparts a unique odor stability to the quaternary.

While the amount of SO₂ needed will vary with the particular preparation of quaternary usually up to two percent SO₂ by weight may be used. The preferred amount is 0.1% by weight.

The invention is more thoroughly described by reference to the following examples which show not only how

2

the invention may be performed but also the limits of SO₂ that are desirable.

In Examples I to VI, the quaternary is freed of solvent using a 200 cc. separatory funnel with ground glass connections fitted upon a five liter resin flask, which in turn is connected to a vacuum system. The quaternary is placed in the separatory funnel and maintained at 90–105° C. Vacuum is then applied to the resin flask and the molten quaternary is slowly admitted to the evacuated resin flask at such a rate that the vacuum is maintained at a relatively steady pressure of 10–20 mm. Hg. The hot molten quaternary under these conditions will rapidly lose its solvent and fall to the bottom of the resin flask as a dry friable powder.

EXAMPLE I

In a one liter 2-necked flask equipped with means for mixing and a reflux condenser are placed 400 g. of dihydrogenated tallow dimethyl ammonium chloride such as Arquad 2HT 75% active, manufactured by Armour and Company, Chicago, Ill. The quaternary is heated until molten and gaseous SO₂ is slowly bubbled in for a period of 135 minutes. The product is then stripped of the solvent, water and isopropanol in the manner described above.

With the above amount of SO₂ the dried product will be found to be strong in residual SO₂ odor. This is obviously undesirable.

EXAMPLES II, III, IV, V

Example I is repeated, but in each of succeeding examples, the SO₂ is successively diminished by bubbling in decreasing periods of 20, 10, 5 and 3 minutes respectively.

However, the dried quaternary is still strong with residual SO₂ odor. So, further reduction is necessary.

EXAMPLE VI

SO₂ is bubbled into a 50:50 mixture of water and isopropanol until a 2 molar SO₂ solution is obtained (12.8% SO₂). 10 cc. of this mixture are then added to 100 g. and 200 g. of 75% Arquad 2HT. The quaternary is dried as previously described and checked for SO₂ odor. In the 100 gram sample, SO₂ could be detected but in the 200 gram sample, SO₂ is no longer detectable. Thus, the proper concentration of SO₂ for Arquad 2HT is determined.

PILOT PLANT EXAMPLES

Examples	Quaternary wt. (lbs.)	SO ₂ used (cc. of 12.8%)	Comments
VII-----	35.0	59	Some quaternary odor still present.
VIII-----	35.0	100	Do.
IX-----	35.0	100	Do.
X-----	35.0	200	Quaternary odor barely discernible.
XI-----	35.0	300	SO ₂ odor.
XII-----	35.0	200	No quaternary odor, but slight SO ₂ odor.
XIII-----	35.0	200	Do.
XIV-----	35.0	200	Do.
XV-----	35.0	150	No quaternary or SO ₂ odor.
XVI-----	35.0	150	Do.
XVII-----	35.0	150	Do.
XVIII-----	140.0	600	Do.
XIX-----	507.0	3280	Do.
XX-----	224.0	896	Do.

The above process is applicable to any fatty quaternary ammonium compound, such as distearyl dimethyl ammonium chloride, disoja dimethyl ammonium chloride, di-coco dimethyl ammonium chloride, cetyl trimethyl ammonium bromide, stearly dimethyl benzyl ammonium chloride, cetyl dimethyl ethyl ammonium bromide, cetyl dimethyl benzyl ammonium chloride, cetyl pyridinium bromide, tetradecylpyridinium bromide, dodecylbenzyl trimethyl ammonium chloride and similar quaternaries.

The solvent out of which the quaternary is dried may comprise any of the customary polar solvents usually used in the syntheses of the quaternary, such as the organic alcohols, particularly ethanol, isopropanol, butanol and the like.

The SO_2 is usually dissolvable in these polar solvents, but one could also utilize a non-polar solvent for the SO_2 , provided it were miscible with the solvent contained in the quaternary being deodorized.

It will thus be seen that the objects set forth above, among those made apparent from the preceding description, are efficiently attained and, since certain changes may be made in carrying out the above method and in the composition set forth without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

What is claimed is:

1. A process for preventing the development of undesirable odor in fatty quaternary ammonium compounds comprising admixing up to 2% by weight of SO_2 in the

presence of solvent to said quaternary ammonium compounds and then drying said compounds of solvent.

2. A process for preventing the development of undesirable odor in fatty quaternary ammonium compounds without imparting a sulfur odor to said compounds comprising admixing about 0.1% by weight of SO_2 in the presence of solvent to said quaternary ammonium compounds and then flash drying said compounds of any solvent.
